UNITED STATES PATENT OFFICE.

EDWARD A. SMITH, OF VALDOSTA, GEORGIA.

TURPENTINE DIP BUCKET.

Application filed December 20, 1926. Serial No. 155,950.

The invention relates to a bucket and more particularly to that class known as dip buckets for turpentine or the like.

The primary object of the invention is the provision of a bucket of this character, wherein the formation thereof is peculiar, and one side of the bucket is provided with a lip, so as to enable the bucket to penetrate the mass of turpentine within a container, so that the bucket will become filled when dipped into the mass, without requiring any exertion on the part of the user of the bucket.

Another object of the invention is the provision of a bucket of this character, wherein the dipping operation is expedited, the bucket in its construction being novel in form and is designed particularly for the dipping of turpentine when collected (in a container).

A further object of the invention is the provision of a bucket of this character, which is extremely simple in its construction, thoroughly reliable and efficient in its purpose, strong, durable, and inexpensive to manufacture.

With these and other objects in view, the invention consists in the features of construction, combination and arrangement of parts, as will be hereinafter more fully described, illustrated in the accompanying drawing, showing the preferred embodiment of the invention, and pointed out in the claims hereunto appended.

In the accompanying drawing:—

Figure 1 is a side elevation of a bucket of the character stated, constructed in accordance with the invention.

Figure 2 is a vertical longitudinal sectional view through the bucket.

Figure 3 is a vertical transverse sectional view through the bucket.

Figure 4 is a sectional view on the line 4—4 of Figure 2, looking in the direction of the arrow.

Figure 5 is a fragmentary rear elevation of the bucket showing in detail the lip thereon.

Similar reference characters indicate corresponding parts throughout the several views in the drawing.

Referring to the drawing in detail, A designates generally the body of the bucket, preferably made from galvanized sheet metal, and B the handle or bail. The body A is substantially semi-oval in plan.

As stated the body A of the bucket is preferably made from sheet metal, although the same may be made from any other suitable material and is of the required size. The body A comprises a bottom 10 and vertical wall sections 11 and 12, respectively. The wall sections 11 and 12 are continuous and the said section 11 is straight and flat, while the section 12 is rounded at its front and has its sides 13 slightly converging toward the section 11. The meeting ends of the sections 11 and 12 are overlapped and seamed at 13' to form a fluid-tight joint. The bottom 10 is joined with the sections 11 and 12 through the medium of an inter-connected curled seam 14 to form a fluid-tight joint therebetween.

The body A can be of any desired height. The wall section 11 is formed with an extension 15 at its top which rises a slight distance above the top of the section 12. The length of the extension 15 is the same as the width of the section 11. The top of the section 12 is turned outwardly and downwardly to provide a reinforcing flange or bead 17, for the mouth edge 16 of such section, see Figures 1, 2, and 3. The wall sections provide a rounded front wall, a flat rear wall and a pair of side walls extending inwardly toward the rear wall.

Mounted against the inner face of the extension 15 and positioned between the opposed parts of the inner face of the section 12 is a blade 18, which constitutes a lip. The outer corners of the blade are bevelled as at 19 and the blade 18 is secured to the extension 15 by holdfast devices 20 which are passed through the blade and extension. The blade 18 projects a substantial distance above the extension 15 and is of uniform width throughout and of a height greater than the height of the extension 15 and further depends below the latter.

Riveted or otherwise fastened exteriorly to the body A below the mouth edge 16 are ears 21 having the upper portions thereof offset and to which are swingingly connected a bail or handle 22, the same being preferably of substantially inverted U-shape, although it may be of any other desirable shape and enables the bucket to be carried in the hands of a user for the transportation of such bucket from one point to another. The ears 21 are located in proximity to the flat straight section 11 of the body A, so that the

latter can be rocked when the handle is gripped to bring the blade 18 in a position whereby it will penetrate the mass of material in a container, which is turpentine, 5 whereby the latter can be accumulated within the bucket.

The blade side of the bucket body A is the confronting side of said bucket relative to the mass of turpentine within a container, 10 when the handle 22 is in position for suspending the bucket body A during the act of dipping, so that the blade 18 will be caused to penetrate the mass of turpentine and will direct and have fluidity thereof within the 15 body for the filling of the latter.

It is thought that the construction and mode of use of the bucket for dipping turpentine will be clearly understood and therefore a more extended explanation has been 20 omitted.

What is claimed is:

1. A turpentine dip bucket comprising a substantially semi-oval shaped body open at its outer end and closed at its lower end 25 by a bottom member, said body including a rounded front wall, a flat rear wall and a pair of side walls extending inwardly toward the rear wall, a lapped seam between said rear wall and one of said side walls, 30 lapped seams between said walls and said bottom member, an extension formed on the outer end of the rear wall and projecting above the other of said walls, and a blade secured to said rear wall and projecting 35 above said extension and constituting a lip.

2. A turpentine dip bucket comprising a substantially semi-oval shaped body open at its outer end and closed at its lower end by a bottom member, said body including a 40 rounded front wall, a flat rear wall and a pair of side walls extending inwardly toward the rear wall, a lapped seam between said rear wall and one of said side walls, lapped seams between said walls and said 45 bottom member, an extension formed on the outer end of the rear wall and projecting above the other of said walls, and a blade secured to said rear wall and projecting above said extension and constituting a lip, said blade arranged between the said side walls.

3. A turpentine dip bucket comprising a substantially semi-oval shaped body open at its outer end and closed at its lower end by 55 a bottom member, said body including a rounded front wall, a flat rear wall and a pair of side walls extending inwardly toward the rear wall, a lapped seam between said rear wall and one of said side walls, lapped 60 seams between said walls and said bottom member, an extension formed on the outer end of the rear wall and projecting above the other of said walls, and a blade secured to said rear wall and projecting above said 65 extension and constituting a lip, said blade

arranged between and depending below the top edges of the side walls, and the means for securing the blade to the rear wall arranged below the top edges of the side walls.

4. A turpentine dip bucket comprising a substantially semi-oval shaped body open at its outer end and having its inner end closed by a bottom member secured therewith, said body including a rounded front wall, a flat rear wall and a pair of side walls extending 70 inwardly toward the rear wall, said rear wall projecting above the side and front walls, a blade positioned against the inner face of the rear wall, between the side walls and extending above the top edge of the rear wall and providing a lip, and a bail connected to the side walls.

5. A turpentine dip bucket comprising a substantially semi-oval shaped body open at its outer end and having its inner end closed by a bottom member secured therewith, said body including a rounded front wall, a flat rear wall and a pair of side walls extending 75 inwardly toward the rear wall, said rear wall projecting above the side and front walls, a blade positioned against the inner face of the rear wall, between the side walls and extending above the top edge of the rear wall and providing a lip, and a bail connected to the side walls. 80

6. A turpentine dip bucket comprising a substantially semi-oval-shaped body open at its outer end and having its inner end closed by a bottom member secured therewith, said body including a rounded front wall, a flat rear wall and a pair of side walls extending 90 inwardly toward the rear wall, said rear wall projecting above the side and front walls, a blade positioned against the inner face of the rear wall, between the side walls and extending above the top edge of the rear wall and providing a lip, and a bail connected to the side walls in proximity to 95 the rear wall.

6. A turpentine dip bucket comprising a substantially semi-oval-shaped body open at its outer end and having its inner end closed by a bottom member secured therewith, said body including a rounded front wall, a flat rear wall and a pair of side walls extending 100 inwardly toward the rear wall, said rear wall projecting above the side and front walls, a blade positioned against the inner face of the rear wall and between the side walls and extending above the top edge of the rear wall and providing a lip, means for securing the blade to the rear wall, a pair of ears secured to the side walls in proximity to the rear wall, and a bail connected to said ears. 105

7. A turpentine dip bucket comprising a substantially semi-oval-shaped body open at its outer end and having its inner end closed by a bottom member secured therewith, said body including a rounded front wall, a flat rear wall and a pair of side walls extending 110 inwardly toward the rear wall, said rear wall projecting above the side and front walls, a blade positioned against the inner face of the rear wall and between the side walls and extending above the top edge of the rear wall and providing a lip, means for securing the blade to the rear wall, a pair of ears secured to the side walls in proximity to the rear walls, a bail connected to said ears, a means for securing the blade to the rear wall positioned below the side walls, and said ears extending above the upper 115 120 125 130 135

ends of the side walls and having the bail connected to the portions thereof positioned above the side walls.

8. A turpentine dip bucket comprising a substantially semi-oval-shaped body open at its outer end and having its inner end closed by a bottom member secured therewith, said body including a rounded front wall, a flat rear wall and a pair of side walls extending inwardly toward the rear wall, said rear wall projecting above the side and front walls, a blade positioned against the inner face of the rear wall and between the side walls and extending above the top edge of

the rear wall and providing a lip, means 15 for securing the blade to the rear wall, a pair of ears secured to the side walls in proximity to the rear walls, a bail connected to said ears, a means for securing the blade to the rear wall positioned below the side walls, 20 said ears extending above the upper ends of the side walls and having the bail connected to the portions thereof positioned above the side walls, and said side and rear walls having the upper ends thereof reinforced. 25

In testimony whereof, I affix my signature hereto.

EDWARD A. SMITH.
